CARBURIZING BOX WITH CENTRIFUGALLY
CAST SIDE WALLS

Henry H. Harris, Champaign, Ill.

Original application May 17, 1935, Serial No. 21,926. Divided and this application March 30, 1936, Serial No. 71,577

2 Claims. (Cl. 263—49)

The present invention relates to carburizing boxes, and particularly to carburizing boxes with centrifugally cast side walls. The present application is a division of my copending application, Serial No. 21,926, filed on May 17, 1935.

The main object of my invention is the provision of a centrifugally cast side walls member for carburizing boxes which is highly dense and substantially free from porosity.

10 Another object of my invention consists in the provision of a centrifugally cast side-walls member for carburizing boxes comprising a continuous integral tube.

A further object of my invention consists in 15 the provision of a centrifugally cast side walls member for carburizing boxes comprising a continuous integral tube free from joints at the corners, polygonally sectioned, preferably rectangular in shape.

20 Another object of my invention consists in the provision of a centrifugally cast tubular member, cut off lengths of which may be formed into side-walls members for carburizing boxes, with extra material added to form thickened parts 25 constituting elemental or longitudinal parts of the completed tubular member, and which constitute reinforcements for strengthening the box at the corners.

A further object of my invention is the provision 30 of a carburizing box the side walls member of which is centrifugally cast and the end or head portion of which is welded thereto to complete the box.

Other objects will appear from the following 35 description of certain illustrative embodiments of the invention shown in the accompanying drawing, in which

Fig. 1 is a cross-sectional view of a centrifugally cast tubular body, lengths of which may be 40 cut off to form side walls of a round carburizing box;

Fig. 2 is a similar view of a modified form of centrifugally cast tubular body deformed into substantially rectangular shape and provided with 45 extra reinforcing material at the corners;

Fig. 3 is a section of the tube of Fig. 2 flattened in parts to form side walls of a substantially rectangular box;

50 Fig. 4 is a vertical sectional view of a carburizing box having centrifugally cast side walls and with an end or head member welded in place, the box being shown set in a tray and containing carburizing compound and parts to be carburized, 55 and

Fig. 5 is a view similar to a portion of Fig. 4, showing a modified form of end or head.

Reference character 10 designates a centrifugally-cast round tubular member which, by being cast in a rotating mold, is subjected in molten state to centrifugal force whereby it is made dense and resistant to carbon penetration. The metal used is of the alloy type adapted to stand up well under the conditions encountered in carburizing work at high temperatures. An alloy metal of 10 nickel-chromium-iron composition, for example, is well adapted for such purpose, and the dense, close texture which is obtained by centrifugal casting enables longer useful carburizing box life to be obtained with given proportions of the alloying metals, such as nickel and chromium, than when casting in the ordinary way with the identical composition. When the side-walls member for the carburizing box is to be round, the centrifugally cast tube 10 for providing such side 20 walls may be of uniform thickness, as shown in Fig. 1.

In a modification, I may provide such a centrifugally cast tubular member 10a as shown in Fig. 2, with lengthwise extending thickened portions 12, 12. In Fig. 2, I have shown four such thickened portions 12, arranged in pairs, and by flattening the longer intermediate portions 14, 14, to form substantially flat sides 16, and flattening out the shorter intermediate portions 18, 18 25 to form substantially flat ends 20, 20 of a side walls member 22 shown in Fig. 3, a thickened wall part and strengthening effect is obtained at the corners, indicated at 12b, 12b. The wall flattening may either be performed on an elongated tube 30 and the tube thereafter cut into lengths to form the side walls member for carburizing boxes of approximately the length indicated at 24, Fig. 4, or the centrifugally cast tubular member may first be cut into lengths, or originally made in 35 lengths suitable for box walls and then side-flattened, the metal being raised to a sufficiently high temperature, though well below the melting point, to permit the operation of flattening out the sides to be performed without cracking or breakage at 40 the corners or elsewhere.

The ends or head members may be made in various ways. Rolled or sheet material may be used if desired, or cast heads 26 of metal similar to that used for the side walls may be provided, 50 and same can be welded into place to close one end of the box. In the form shown in Fig. 4 the cast head 26 comprises side walls or flanges 28 of substantially the same diameter as the side wall members and forming substantially continu- 55

ations of said side walls of the box when welded thereto as indicated at 30. In Fig. 5, the head 26a is made somewhat larger so that the side wall flange 28a thereof encompasses the side wall member of the box and same are welded together interiorly and exteriorly at 34 and 36 respectively, but in each case the shape of the head member is identical with that of the side walls portion.

For use, the boxes with closed end 26 down are usually loaded with pieces 38 to be carburized and carburizing compound 40, the tray 42 set on top, and the whole then inverted into the position shown in Fig. 4. The heads 26, 26a, may be provided with feet 44, 44a if desired.

15 Further modifications within the scope of my claims are included within my invention.

Having described my invention what I claim and desire to secure by Letters Patent is:

1. A carburizing box comprising a many-sided

centrifugally cast hollow prism forming the side walls portion of said box, said sides being substantially flat and having substantially integral thickened parts extending lengthwise thereof at the outside defining corners of the box and having a head member of similar shape welded thereto for closing an end thereof.

2. A carburizing box comprising a centrifugally cast integral side walls member with substantially thickened parts on the outside defining corners of the box from the top to the bottom thereof, the portions between the corners being substantially flat, having a similarly shaped head member welded thereto at and closing one end of the side walls member, said head portion being thickened at the corners to correspond with the thickening on the side walls member.

HENRY H. HARRIS.
